JOHN G. CALLAN, OF LYNN, MASSACHUSETTS, ASSIGNOR TO GENERAL ELECTRIC COMPANY, A CORPORATION OF NEW YORK.

VALVE MECHANISM FOR TURBINES.

No. 841,224.

Specification of Letters Patent.

Patented Jan. 15, 1907.

Application filed August 5, 1904. Serial No. 219,586.

To all whom it may concern:

Be it known that I, JOHN G. CALLAN, a citizen of the United States, residing at Lynn, county of Essex, State of Massachusetts, have invented certain new and useful Improvements in Valve Mechanism for Elastic-Fluid Turbines, of which the following is a specification.

The present invention has for its object to provide a valve mechanism which is normally responsive to pressure conditions for maintaining a relation as to pressure between stages in a multistage turbine, but which may be positively controlled when the conditions of service become abnormal.

The importance of maintaining a reasonably constant pressure on each stage will readily be seen when it is considered that in designing the machine the nozzles and bucket-spaces or working passages are assumed to work at predetermined pressures, and any substantial change therefrom will obviously affect the economy.

In carrying out the invention the turbine is divided into stages by suitable means, and in each stage is located one or more rows of wheel-buckets. Where two or more rows are provided, a row of intermediate buckets is situated between each two rows of wheel-buckets. Fluid is delivered to the first-stage wheel or wheels by one or more inlet-nozzles of suitable construction. Each nozzle is preferably, although not necessarily, composed of a plurality of closely-associated passages which may expand or not, as desired. Fluid exhausting from one stage is collected in the wheel-chamber or in a separate chamber and discharged into the next by nozzles of suitable construction. The nozzles of the several stages may be, and usually are, of similar construction, those of the lower-pressure stages, however, having a greater area in cross-section. A part of the nozzles may be in permanent communication with the succeeding wheel-chamber, while one or more of the balance are under the control of a valve or valves which are normally automatic in their action and are responsive to pressure changes, but which may be manually or otherwise positively controlled or actuated when desired. Those nozzles or nozzle-sections which are valve-controlled are supplied

with fluid from a chamber that may with advantage be formed in a cover-plate that is preferably secured to the same support as the nozzle or nozzles. On the plate or supported thereby are seats for the valves, and the means for actuating the valves are controllable from the outside of the whole casing. The valves are normally operated automatically by devices responsive to fluid-pressure changes, such as diaphragms or equivalent means, and under abnormal conditions by hand or power driven wheels which render said automatic feature inoperative. A separate device may be, and preferably is, employed to adjust the means, such as a spring or weight, which opposes the action of the valve-actuating devices. I prefer to use diaphragms because they do not require to be packed, are simple in construction, reliable in operation, and are sensitive to small changes in pressure. The valves are so constructed and arranged that one or all may be held in the open or closed position for abnormal conditions, or one valve may operate automatically while the other or others are held open or closed. The valves may be slightly unbalanced, which causes them to have a tendency at all times to close. The more nearly the valves are balanced the less will be the work required of the devices for actuating them.

In order to prevent undue shock when the valves operate, a dash-pot is provided for each. The valves are normally set to operate successively under different pressures by changing the tension on the spring or varying the weight, and the number of nozzles or nozzle-passages controlled by each valve may be and preferably is greater in one case than the other or others.

In the accompanying drawings, which illustrate one embodiment of my invention, Figure 1 is a vertical longitudinal section of a jet-turbine. Fig. 2 is a partial cross-section of the same. Fig. 3 is a detailed view taken on line 3-3 of Fig. 1. Fig. 4 is a detailed sectional view taken on the line 4-4 of Fig. 1, and Fig. 5 shows a plurality of separately-actuated valves for controlling the admission of motive fluid to the turbine.

1 represents the casing of the turbine, which is divided into compartments by one

or more partitions or diaphragms 2. The one shown is in the nature of a box with a chamber between its walls. The head of the machine is provided with a flange 3, to which is bolted a sectionalized nozzle 4, each section of said nozzle being provided with a well-rounded bowl and a gradually-diverging passage which receives fluid from the bowl and discharges it at the proper angle against the wheel-buckets. Located in the wheel-compartment adjacent to the nozzle is a wheel 5, having two rows of peripheral buckets, and between the rows of wheel-buckets is a row of intermediate buckets 6, which may extend partially or wholly around the wheel. These buckets are carried by a support 7, that is attached to the outside of the casing. The buckets are arranged to fractionally abstract the velocity of the motive fluid discharged from the nozzles. The fluid exhausting from the wheel passes through the port 8 into the chamber 9, formed between the diaphragms. The second-stage wheel 10 is similar in construction to the first-stage wheel, except that the bucket spaces or passages are usually larger, and intermediate buckets 11 are provided which extend partially or wholly around the wheel, as desired. The wheels may be mounted on the same or on a different shaft. The steam or other elastic fluid exhausted from the second wheel passes through the port 12 and is discharged into a condenser or into the atmosphere, as is desired.

Bolted to the diaphragm or partition which separates the wheel-compartments is a nozzle 13, which is similar in construction to nozzle 4, the only difference being that the bowls and passages are made somewhat larger to accommodate the increased volume of motive fluid. Bolted or otherwise attached to the nozzle is a valve plate or cover 14, containing one or more chambers 15, which convey motive fluid to the second-stage nozzle. In the present instance two of these chambers are employed. Chamber 15 supplies fluid to two nozzle-sections, while chamber 16 supplies fluid to three nozzle-sections, but this arrangement can be modified.

The upper surface of the valve plate or cover is provided with as many screw-threaded openings as there are valves, and mounted therein are valve-seats 17. In the present illustration each valve is provided with a double seat, one being located above the other. The valve 18 is slightly unbalanced and is arranged to make contact with the upper and lower seats. It is guided in its movements at the lower end by a projection 19, that is carried by the valve-seat. To the upper end of the valve is attached a valve-stem 20, which is screw-threaded at its lower end to receive the piston-like head 21;

that engages with the upper side of the diaphragm 22. Mounted on the stem and situated below the valve is a head 23, having a curved upper surface which engages with the diaphragm. The object of this head is to distribute the strain over the diaphragm, thereby reducing the liability of rupture. Surrounding the piston 21 and clamping the diaphragm in place is a casing 24, containing a certain amount of fluid, such as oil or water, which acts to prevent undue shocks to the valve at the time it operates.

The cylindrical guiding-wall of the piston is perforated at one or more points 25, which permits the fluid to be transferred from one side of the piston-head into the chamber formed therein when the diaphragm moves the valve. Surrounding the valve-stem and resting on the hub of the piston is a collar 26, which forms a seat for the lower end of the compression-spring 27. The upper end of the spring engages with an adjustable nut 28, that is threaded to a cylindrical wall on the casing 24. The forces exerted by the spring and the diaphragm are so related to each other that a predetermined change in pressure in the chamber 9 will cause the valve to open or close. By adjusting the parts any desired relation can be maintained.

Surrounding the valve-stem and passing through the nut is a screw-threaded sleeve 29. Surrounding the sleeve and threaded thereon is a nut 30, which is attached to a wheel that is moved by hand or power. The lower end of the nut is provided with a groove, and entering the groove are fingers 31, which permit the nut to rotate, but prevent it from moving longitudinally.

Mounted on the valve-stem at a point below the sleeve is a collar 32, which when the sleeve is moved downward acts as an abutment therefor and permits the positive closing of the valve irrespective of the pressure in the chamber 9. The upper end of the valve-stem is provided with a shoulder or abutment 33, against which the sleeve strikes when raised by the rotation of the hand-wheel. When the sleeve engages the shoulder 33, it opens the valve irrespective of the pressure on the diaphragm. To state the matter in a different way, a lost-motion connection is provided between the hand-wheel and the valve, so that when the latter is properly set it permits the valve to freely open and close under the action of the diaphragm and spring. From this it will be seen that the valve can operate automatically or be closed by the hand-wheel irrespective of the pressure on the diaphragm, or it can be opened as desired.

The specific action of each valve is as follows: Tending to open the valve is the first-stage shell-pressure multiplied by the diaphragm area and a constant, (since the dia-

phragm does not move upward bodily,) plus the second-stage shell-pressure multiplied by the difference in area of the two valve-seats. Tending to close the valve is the difference in area of the valve-seats multiplied by the first-stage shell-pressure, plus the spring-pressure, this condition existing when the valve is shut. When the valve is open, there is tending to hold it in this position the first-stage shell-pressure times the diaphragm-area times a constant. Tending to close it is the somewhat-augmented spring-pressure. Obviously then since the unbalanced valve-area disappears when the valve is open the valve will stay in this position on a first-stage shell-pressure considerably less than that which will cause it to open, and this difference can be made small or large, as desired. It should, however, be sufficient in amount so that the drop in the shell or wheel compartment pressure due to the opening of the new nozzles will not be sufficient to cause the valve to close.

Fluid is admitted to the turbine by separately-actuated valves in response to movements of a suitable governor—as, for example, a fly-ball governor. I may and preferably do employ diaphragm-actuated valves for controlling the admission of fluid to the

30 turbine.

In Fig. 5 is shown a plurality of separately-actuated valves for varying the amount of motive fluid admitted to the first wheel of the turbine. The same type of valve may be employed between any two stages in addition to the pressure-actuated valves, if desired.

34 represents the valve which is attached to an operating device or stem 35. The 40 valves are controlled by a device responsive to speed changes, and this control may be direct or indirect, as through the intervention of motors, valves, magnets, &c.

36 represents the valve-chest, and 37 the 45 passages in the nozzle. Opening and closing these valves causes a change in pressure in the chamber 9, and a change in the latter causes the valves 18 to open and close.

In accordance with the provisions of the 50 patent statutes I have described the principle of operation of my invention together with the apparatus which I now consider to represent the best embodiment thereof; but I desire to have it understood that the apparatus shown is only illustrative and that the invention can be carried out by other means.

What I claim as new, and desire to secure by Letters Patent of the United States, is—

1. An elastic-fluid turbine comprising a 60 casing, means for dividing it into compartments, and wheels located in compartments, in combination with a valve automatically responding to pressure changes located in a compartment situated between the wheels.

2. An elastic-fluid turbine comprising a 65 casing containing wheels located in compartments, in combination with a chamber between said compartments, into which a wheel discharges, and a valve automatically responding to pressure changes located in the 70 chamber for controlling the passage of fluid to a wheel.

3. An elastic-fluid turbine comprising a 75 casing containing wheels located in compartments, in combination with a chamber formed within the casing and between the compartments which is in open communication with one of the latter to receive the exhaust therefrom, a valve located in the chamber for controlling the passage of motive fluid 80 from the chamber to another compartment, automatic means for operating the valve, and a dash-pot for the valve.

4. An elastic-fluid turbine comprising a 85 casing containing wheels located in compartments, in combination with a chamber located within the casing communicating with a compartment to receive the exhaust therefrom, an automatic valve controlling the passage of fluid through the chamber, and positively operated means for holding said automatic valve in either a closed or open position.

5. An elastic-fluid turbine comprising relatively movable elements and a casing therefor, in combination with a valve, automatic means for opening and closing the valve in response to predetermined changes in operating conditions, and a device for opening or closing the valve positively and rendering 95 said automatic means inoperative.

6. An elastic-fluid turbine comprising relatively movable elements and a casing therefor, in combination with a valve, a motor responsive to changes in fluid-pressure for operating the valve, and a device located outside of the casing for opening or closing the valve against said fluid-pressure.

7. An elastic-fluid turbine comprising relatively movable elements and a casing therefor, in combination with a valve, a fluid-actuated motor for automatically operating the valve, and a device for actuating the valve independently of said motor, which includes a lost-motion connection.

8. An elastic-fluid turbine comprising relatively movable elements and a casing therefor, in combination with a plurality of successively-operating valves within the casing which control the passage of fluid from one 120 element to the other, and a dash-pot for each valve for checking the movements thereof.

9. In an elastic-fluid turbine, the combination of a casing divided into stages, a valve between stages, a fluid-actuated motor for 125 moving the valve, which responds to changes in pressure of one of the stages, and a means located outside of the turbine-casing by

means of which the valve can be opened or closed.

10. In an elastic-fluid turbine, the combination of a casing which is divided into 5 stages, nozzles which receive fluid from one stage and discharge it into another, a covering for the nozzles, a valve controlling the passage of fluid through the nozzles, and a seat for the valve, which is supported by the 10 covering.

11. In an elastic-fluid turbine, the combination of a casing which is divided into stages, nozzles which receive fluid from one stage and discharge it into another, a covering for the 15 nozzles, which is divided into compartments, and a valve for each compartment.

12. In an elastic-fluid turbine, the combination of a casing, which is divided into stages, nozzles which receive fluid from one stage and 20 discharge it into another, a covering for the nozzles, which is divided into compartments, a valve for each compartment, and a seat for each valve, which is carried by the covering.

13. In an elastic-fluid turbine, the combination of a casing, a wall dividing the casing 25 into compartments, a nozzle supported by the wall, a valve, a seat for the valve removably supported by the wall, and means for operating the valve.

30. 14. In an elastic-fluid turbine, the combination of a casing, a wall for dividing the casing into stages or compartments, a valve for controlling the passage of fluid between compartments, a stem for the valve, a sleeve 35 around the stem, the sleeve and stem being capable of longitudinal movement, stops on the stem, and means for moving the sleeve into engagement with either of the stops.

15. In an elastic-fluid turbine, the combination of a casing, a wall for dividing the casing 40 into stages or compartments, a valve for controlling the passage of fluid between compartments, a diaphragm for actuating the valve in response to changes in stage-pressure, a stem for actuating the valve positively, and means located outside of the casing 45 for moving the stem.

16. In an elastic-fluid turbine, the combination of a casing, a wall for dividing the casing 50 into stages or compartments, a balanced valve located within the casing and between the compartments, a motor for actuating the valve in response to changes in pressure of the motive fluid, a spring which urges the 55 valve in one direction, a dash-pot for the valve, a means for positively actuating the valve, and a lost-motion connection between the valve and said means.

17. In an elastic-fluid turbine, the combination of a casing, partitions or walls for 60 dividing the casing into stages, a valve for varying the admission of motive fluid to the turbine, and diaphragm-actuated valves con-

trolled by stage-pressure for varying the passage of fluid from one stage to another. 65

18. In an elastic-fluid turbine, the combination of a casing, which is divided into stages, a plurality of separately-actuated valves for varying the admission of motive fluid to the turbine, and independent diaphragm-actuated valves for controlling the passage of fluid between one stage and the next which are actuated by stage-pressure. 70

19. In an elastic-fluid turbine, the combination of a casing, walls which divide the casing 75 into wheel-compartments and form a chamber intermediate the latter, nozzles which discharge from the chamber to one of the compartments, certain of the nozzles being permanently open, and a valve or valves 80 controlling the remaining nozzles.

20. In an elastic-fluid turbine, the combination of a sectionalized nozzle, certain of whose discharge-passages are adapted to deliver motive fluid continuously, a ported 85 cover for the remaining passage or passages, and a valve for controlling the admission of motive fluid to the covered passage or passages.

21. In an elastic-fluid turbine, the combination of a sectionalized nozzle, certain of whose discharge-passages are adapted to deliver motive fluid continuously, a ported and partitioned covering for the remaining passages of the nozzle, and a plurality of valves 95 for controlling the admission of motive fluid to the covered passages. 90

22. In an elastic-fluid turbine, the combination of a group of closely-associated fluid-discharging passages, a cover arranged over 100 certain of the passages at the inlet ends thereof, means for dividing the cover into compartments, and a valve for each compartment controlling the admission of fluid thereto. 105

23. In an elastic-fluid turbine, the combination of a sectionalized nozzle comprising a group of closely-associated fluid-discharging passages, a support to which the nozzle is removably secured, a ported cover for certain of the fluid-discharging passages which is removably secured to the nozzle, and a valve 110 for controlling the supply of motive fluid to the covered passages. 115

24. In an elastic-fluid turbine, the combination of stage-compartments, a bucket-wheel in each stage-compartment, a chamber which receives the exhaust from a wheel and prevents it from reacting thereon, devices which receive fluid from the chamber and discharge it to a wheel at a lower pressure, auxiliary nozzles, and a stage-valve which controls the passage of fluid from the chamber to the auxiliary nozzles. 120

25. In an elastic-fluid turbine, the combination of two or more stages, a bucket-wheel 125

in each stage-compartment, a chamber which receives the exhaust from a wheel and prevents it from reacting thereon, devices which receive fluid from the chamber and discharge it to a wheel of lower pressure, auxiliary nozzles, and a plurality of valves which are responsive to variations in stage-pressure and operate successively to control the passage of

fluid from the said chamber to the auxiliary nozzles.

In witness whereof I have hereunto set my hand this 19th day of July, 1904.

JOHN G. CALLAN.
